UNITED STATES PATENT OFFICE

102,429

DESIGN FOR A SOCK FASTENER FOR GARTERS

Walter W. Hartmann, Los Angeles, Calif., as-
signor to Sara A. Philips, Los Angeles, Calif.

Application November 19, 1935, Serial No. 59,649

Term of patent 3½ years

To all whom it may concern:

Be it known that I, Walter W. Hartmann, a citizen of the United States, residing at Los Angeles and State of California, have invented a new, original, and ornamental Design for Sock Fastener for Garters, of which the following is a specification, reference being had to the accompanying drawing, forming part thereof.

Fig. 1 is a front view, and Fig. 2 a side view of a sock fastener for garters, showing my new design.

The dominant features of the design reside in the contour of the rounded ends of the upper or slotted part of the fastener which converge into a narrow intermediate portion, while from this portion the spurred section of the fastener is first reversely curved outward and then inward to meet a rounded lower end.

I claim:

The ornamental design for a sock fastener for garters, as shown and described.

WALTER W. HARTMANN.
